MACHINE-TOOL GUARD

Edward J. Kearney, deceased, late of Wauwatosa, Wis., by Otto W. Carpenter, Jr., special administrator, Fox Point, Wis., and Joseph E. Armistage, Wauwatosa, Wis., and Walter M. Pohl, Hamden, Conn., assignors to Kearney & Trecker Corporation, West Allis, Wis., a corporation of Wisconsin

Original application June 8, 1938, Serial No. 212,704, now Patent No. 2,355,082, dated August 8, 1944. Divided and this application July 6, 1944, Serial No. 543,681

5 Claims. (Cl. 90--11)

1

This invention relates generally to machine tools, and more particularly to an improved guard for the cutter of a machine tool.

The present specification constitutes a division of application Serial No. 212,704, filed June 8, 1938, now Patent No. 2,355,082, dated August 8, 1944.

A general object of this invention is to provide an improved cutter guard for a machine tool.

Another object of the invention is to provide a hingedly mounted guard capable of swinging movement upon being engaged by a moving member.

Another object of the invention is to provide an adjustable guard disposed for selective positioning relative to the various machine members.

Another object of the invention is to provide a machine guard especially adapted to protect the machine operator and to confine flying chips or other matter.

Another object of the invention is to provide a guard, which may be removed readily to facilitate access to the machine while it is being set up, cleaned or repaired.

According to this invention, a guard is provided which may be adapted to any type of machine tool or other machine, wherein it is necessary to provide protection to the machine operator from contact with moving machine parts and from flying chips, coolant liquids and other material. The guard is constituted by transparent panels pivotally suspended from a cross member that is adjustably supported at its ends upon upstanding posts. By raising or lowering the cross member, the position of the guard may be adjusted to adapt it to the particular work at hand. Since the guard panels are pivotally mounted, they may be positioned close to the work, with assurance that they will swing aside if struck. The end posts are so mounted on the machine that the entire guard may be removed readily to afford access to the machine elements.

The foregoing and other objects of this invention, which will become more fully apparent from the following detailed description, may be achieved by means of the exemplifying apparatus depicted in, and set forth in this specification, in connection with the accompanying drawings, in which:

Figure 1 is a side elevational view of a machine tool provided with a guard embodying the present invention;

Figure 2 is a top plan view of the machine tool shown in Figure 1; and

Figure 3 is a view partly in front elevation

2

and partly in vertical section, showing details of the guard structure.

Referring more specifically to the drawings, Figures 1 and 2 thereof show the general structure of a milling machine provided with a guard constructed in accordance with the principles of this invention and particularly referred to herein, by way of example. As there shown, the machine is of the continuously operating type and comprises essentially a bed or base 30, having secured at its back an upstanding spindle-supporting column 31, which carries an adjustably mounted tool spindle 32. Rotatably mounted on the top of the bed 30, in front of the column 31, is a horizontally disposed circular work-supporting table 33, carrying a pair of work-holding fixtures 34 and 35 disposed thereon in diametrically opposed relationship.

The two work-holding fixtures 34 and 35 are supported on the table 33, in manner to be movable radially thereof, by means of a reciprocating cross slide 37, that is slidably mounted diametrically of the table, as shown in Figure 2, the fixtures being rotatably mounted near the respective ends of the slide. By this arrangement, the work-holding fixtures are movably mounted on the table 33, in such manner that when the table is rotated, the fixtures in turning with it may be guided successively through the cutting zone along a predetermined path.

In the particular structure shown, the two work-holders 34 and 35 are caused to follow a straight line path through the cutting zone, as the table is rotated, the fixtures each having a compound motion, by reason of the sliding and turning movements provided by its rotatable mounting on the reciprocating cross slide 37. This arrangement provides for feeding work pieces successively in the same direction, along the straight line path through the cutting zone, and then leading them away, without the necessity of withdrawing them past the cutter.

The cutter supporting spindle 32 is arranged to be adjusted relative to the work table 33, both in vertical direction and transversely of the path of movement of the work-holding fixtures 34 and 35 through the cutting zone. To provide for the vertical adjustment, the supporting spindle is carried by a spindle head 42, which is slidably mounted on the column 31, a hand wheel 44 serving to operate mechanism for moving the head vertically along the column, in a well known manner. To provide for adjusting the spindle transversely of the cutting path, it is rotatably mounted by means of anti-friction thrust bear-

ings in a quill, which is slidably mounted for axial adjustment in the spindle head 42, a manually operated mechanism 51 being provided for effecting the adjustment in a well known manner. The usual overarms 54 are slidably mounted in the upper part of the spindle head 42, in position to carry a depending arbor support 55, in which the end of an arbor 56, carrying a cutter 57, is rotatably supported.

In operating the machine, the work-holding fixture, which happens to be in the forward position or loading station, may be loaded with a work piece while the table is turning slowly at feed rate. At the end of the feeding stroke, the table is automatically turned at rapid traverse rate, to cause the work piece to approach quickly to a position closely adjacent to the rotating cutter 57, the work piece being clamped automatically as the table is turned. The rate of table movement is then automatically changed back to feed rate, in order to feed the work piece along the straight line path, through the cutting zone, in operative engagement with the cutter 57.

After the work piece has passed the cutter, the table is again automatically moved at rapid traverse rate, in the same direction, to quickly lead away the finished work piece and to bring it around to the forward position for unloading, a new work piece in the other fixture, meanwhile, being moved simultaneously into position for feeding to the cutter. By this arrangement, the work table may be turned continuously in the same direction, alternately at rapid traverse rate and at feed rate, with the cutter rotating to effect substantially continuous milling of successive work pieces.

The details of construction of the mechanism for effecting automatic movement of successive work pieces past the cutter of this machine and its mode of operation are more fully set forth in the previously-mentioned parent application, which resulted in Patent No. 2,355,082.

The particular machine tool herein set forth is exemplary of apparatus with which the guard embodying the present invention may be utilized to advantage, although it is to be understood that the guard is readily adaptable to other machine tools or similar machinery.

The machine guard to which this invention is particularly directed serves to protect the machine operator from contact with the cutter and from chips, coolant liquid, or other material that may be thrown from the cutter. As utilized in connection with the milling machine herein set forth, the guard structure is mounted around the cutting zone, as shown in Figures 1 and 2. The structure includes a removable back plate 69 that cooperates with an apron attached to the spindle head 42 in closing the back of the cutting zone on the machine, one edge of the plate being slidably fitted in a groove 61 in the right side of the vertically movable head 42. With this arrangement, the head may be adjusted vertically, without disturbing the plate 69. The other edge of the guard back plate 69 is slidably fitted in a slot 62 in a corner post 63, removably mounted in the right rear corner of the bed 30, as shown in Figure 2.

At the sides of the bed 30, the cutting zone is enclosed by removably mounted side plates 65 and 66, respectively, the plate 65 being slidably engaged in another slot or groove 67 of the corner post 63 and a similar groove 68 in a forward corner post or end post 69, while the plate 66 is fitted at one edge in a slot 70 (Figure 2) in

the column 31 and at its other edge in a slot 71 in another forward corner post or end post 72. The plates 65, 66 and 68 are readily removable by sliding them upwardly in their respective retaining slots, to provide access to the cutting zone for changing cutters, making adjustments or the like.

The front of the cutting zone is guarded by means of a shield 75, which extends across the machine between the two front corner posts 69 and 72, as shown in Figures 2 and 3. This shield or guard consists of a crossbar 76, carrying three depending guard plates or transparent panels 77, 78 and 79, preferably of non-shatterable safety glass, or the like. The ends of the crossbar 76 have threaded engagement with vertically disposed threaded shafts or adjusting screws 82 and 83, journeled longitudinally in the corner posts 69 and 72, respectively, the screws being operative to move the shield vertically for adjusting its position to correspond with the vertical position of the cutter 57 and the position of the work pieces retained in the work-holding fixtures 34 and 35. In the present instance, the center panel 78 may be fixed to the crossbar 76, but the end panels 77 and 79 are preferably pivotally mounted thereon, in order that they may swing freely, in the event they should be struck by a work piece, to obviate danger of damage to the machine or injury to the operator. To provide the desired pivotal movement of each end panel, one member of a hinge 84 is attached to the crossbar 76, while the panel is suspended vertically from the other member thereof.

As shown in Figure 3, each of the three panels 77, 78 and 79 is mounted in a frame member 85, in such manner that the edges of the transparent material are protected on both sides to preclude injury to them in the event of contact with the work pieces or parts of the work-holding fixtures 34 and 35. However, this structure may be varied, in that the panels may be made of other suitable material to which the movable member of the hinge 84 may be attached, in any desired manner.

In certain machine operations, especially where a considerable amount of cutter coolant is used, the adjustable crossbar 76 may be lowered sufficiently to practically eliminate the open areas below the panels. Even though the end panels 50 are struck by the work pieces or the work-holding fixtures, as they are rotated through the cutting zone, their pivotal mounting will permit swinging movement and thereby prevent injury to the machine or its operator.

The guard herein disclosed is readily removable from the machine, to permit setting up work and to facilitate adjustments or repairs to any of the work-retaining units or to the cutter and spindle. To this end, the corner posts 69 and 72 are each fitted in a socket 86 (Figure 3) in the top of the machine bed 30, in such manner that they may be removed readily, whenever it is desired to remove the front shield 75 from the machine, the entire shield being lifted as a unit, to withdraw the corner posts from their sockets. The rear corner post 63 is mounted in the same manner and may be removed from the machine bed 30 after the back plate 69 and the side plate 65 have been withdrawn from the slots.

Although the foregoing description and the accompanying drawings set forth the present invention as applied to the particular machine tool described herein, it is to be understood that the structure shown and described is intended to be illustrative of an operative embodiment of the

invention, and that it is contemplated that the various features may be incorporated in other machine structures, without departing from the spirit and scope of the invention, as defined in the subjoined claims.

The invention is hereby claimed as follows:

1. A guard for a machine tool, comprising spaced upstanding end posts, a threaded shaft journalled longitudinally in each of said end posts, a cross bar extending between said posts and having threaded engagement at its ends with said threaded shafts whereby said bar may be adjustably positioned vertically by turning said shafts, and a plurality of guard plates pivotally suspended from said cross bar.

2. In a machine tool, a base, a work supporting member movably mounted on said base, a cutter carrying head slidably mounted for vertical movement on said base, a guard for said machine comprising a plurality of posts upstanding from said base, a guard plate vertically disposed between one of said posts and said head and arranged for vertical sliding movement relative thereto, other guard plates disposed between others of said posts, a cross member adjustably supported at its ends upon two of said posts, and a plurality of transparent guard panels pivotally suspended from said adjustable cross member, whereby the area of cooperative action between said cutter carrying head and said work supporting member is effectively enclosed without interfering with observation or with movement of said work supporting member or of said cutter carrying head.

3. In a machine tool, a base, a column upstanding from said base, a work supporting table rotatably mounted on said base, a cutter carrying head slidably mounted for vertical movement on said column in cooperating relationship with said table, a guard structure including posts upstanding from said base at opposite sides of said table, a guard plate extending from one of said posts to said column along one side of said table, a guard plate extending from the other of said posts along the other side of said table, guard means extending from said last-mentioned guard plate to and having sliding engagement with said cutter carrying head, a cross bar extending from one to the other of said posts, and a plurality of transparent guard plates pivotally suspended from said cross bar above said table, whereby the area of cooperative action between said table and said cutter carrying head is effectively enclosed without interfering with observation thereof or with movement of work pieces into or out of said area.

4. In a milling machine of the bed type having a base, a column upstanding from said base, a cutter carrying head slidably mounted for ver-

tical movement on said column, and a work table movably mounted on said base in cooperating relationship with said head, a guard structure for confining a milling cutter carried by said head, comprising supporting columns mounted on said base at opposite sides of said table, a guard plate closure structure fitted in one of said columns at one end and having sliding engagement with said vertically slidable head at the other end, a cross bar adjustably mounted for vertical movement upon said supporting columns, and a plurality of transparent guard plates pivotally suspended from said cross bar above said table, the arrangement being such that both said cutter head and said suspended guard plates may be adjusted independently to accommodate them to a particular workpiece on said table.

5. In a milling machine, a base, a column upstanding from said base, a cutter carrying head slidably mounted for vertical movement on said column, a rotary work supporting table rotatably mounted on said base in cooperating relationship with said cutter carrying head, a guard structure for confining a milling operation by a cutter carried by said head upon a workpiece on said table, comprising end posts upstanding from said base at opposite sides of said table, a cross bar extending across said table with its ends adjustably supported by said end posts for vertical movement, a plurality of transparent guard plates pivotally suspended from said cross bar above said table, a guard plate extending from one of said end posts to said column forming a closure along one side of said table, a corner post upstanding from said base adjacent to said cutter head, a guard plate slidably fitted to said corner post and to the other of said end posts forming a closure along the other side of said table, and a guard plate slidably fitted to said corner post and to said vertically movable cutter head and forming a rear closure.

OTTO W. CARPENTER, JR.
Special Administrator of the Estate of Edward
J. Kearney, Deceased.
